ELECTRODE CONTACT

Edward W. Forstrom, Stratford, Conn., assignor
to General Electric Company, a corporation of
New York

Application June 26, 1944, Serial No. 542,119

7 Claims. (Cl. 173—328)

1 My invention relates to ultra high frequency discharge devices and, in particular, to contacts for the electrodes of such devices.

It is known in the construction of ultra high frequency electron discharge devices of the type employing cavity resonators as external circuits to arrange the electrodes of the device in spaced axial alignment and to form the external terminals for the electrodes as disk-like members having a step-wise configuration. Such a configuration facilitates insertion of the devices into a cavity resonator.

It is an object of the present invention to provide improved contacts for the electrodes of such devices which allow for considerable variation or eccentricity in the manufacture of the devices.

It is another object of my invention to provide a new and improved resilient supporting and contact-making arrangement for an ultra high frequency electron discharge device which automatically corrects for both vertical and lateral eccentricities in the electrodes of the device.

It is a further object of my invention to provide a new and improved contact for a disk-like electrode.

It is still another object of my invention to provide a new and improved resiliently supported contact for a tubular electrode.

One of the features of the invention includes the use of an anode clip in the form of a pair of bifurcated fingers which are supported by a flexible metallic loop to permit alignment both vertically and laterally. Another feature consists in the use of a contact for a disk-like grid electrode which includes a plurality of resilient fingers mounted on the inner surface of a tubular conductive member, the fingers being provided with surfaces formed to preclude catching of the rings of the disk electrodes on the fingers with attendant injury to the glass-to-metal seals of the device.

For a better understanding of my invention, reference may be had to the following description taken in connection with the accompanying drawing and its scope will be pointed out in the appended claims. Fig. 1 is a vertical view, partly in cross-section, showing an ultra high frequency electron discharge device and the resonant cavity employed therewith which include the electrode contacts of the invention; Fig. 2 is a perspective view of the contact arrangement for a disk-like electrode; and Fig. 3 illustrates one of the elements employed in the contact arrangement of Fig. 2. Fig. 4 illustrates a blank used in forming a contact for a tubular electrode and Fig. 5 is a

2 plan view of the tubular electrode contact as assembled.

Referring particularly to Fig. 1 of the drawing, there is shown an ultra high frequency electron discharge device 1 inserted into an ultra high frequency circuit of the cavity resonator type. The ultra high frequency electron discharge device 1 comprises a thermionic cathode 2, an anode 3, and an interposed grid electrode 4. The cathode is connected for high frequency currents to a cylindrical external electrode 5, the grid is connected to a disk-like electrode 6, and the anode is connected to a tubular electrode 7 having at its base portion a disk-like flange 8. The external electrode connections are maintained in spaced relation by a plurality of insulating cylinders 9, 10, hermetically sealed therebetween.

The cavity resonator for the device 1 is illustrated as of the radial transmission line type and comprises an anode-grid cavity resonator 11 and a grid-cathode cavity resonator 12 having a common metallic boundary 13. The grid electrode disk 6 is connected to the metallic boundary 13 through a contact arrangement 14 illustrated in detail in Fig. 2 and to be described more fully hereinafter. The tubular anode electrode 7 is provided with a flexibly supported contact 15 mounted on fixed supports 16 and to which energizing potential is supplied by means of a contact tab 17. High frequency connection of the cathode contact 5 with the walls of the cathode-grid resonator 12 is provided by means of a plurality of spring-like fingers 18 which are adapted to engage the cylinder 5 and abut against a shoulder 19 at the base of the tube 1. Currents for the filament heater and cathode of the device 1 may be supplied over a plurality of external lead-in conductors 20 extending from the base of the tube.

In the operation of high frequency circuits of the type described, it frequently becomes necessary to change tubes. It is desirable, therefore, to permit a flexible contact arrangement with the electrodes of the tube which compensates for eccentricities of disk electrodes, such as the electrode 6, and variations in length and eccentricities of tubular electrodes, such as the electrode 7, as well as differences in spacing between electrodes due to variations in the length of insulating tubes 9 and 10. A contact for a disk-like electrode which permits a wide amount of eccentricity in the electrode, as well as variation in its longitudinal position, is shown in Fig. 2. The grid contact arrangement 14 there illustrated comprises a flat plate member 21 having a cen-

tral aperture 22. A conductive flange 23, which may be formed integrally with the plate 21 and which extends perpendicular to that plate, has a diameter substantially larger than the diameter of any disk-like electrode which the contact arrangement is adapted to receive. Attached to the inner surface of the flange or tubular member 23, as by means of rivets 24, are a plurality of resilient contact members 25. In the arrangement shown in Fig. 2, twelve such contact members are provided.

An individual contact member 25 is shown in enlarged view in Fig. 3 and comprises a base portion 26 having a pair of apertures 27 for receiving the rivets which attach it to the conductive flange 23 and a resilient C-shaped finger 28 attached to the base portion 26 by an arm 29 and inclined to the base portion at an angle of from 20° to 60°. Preferably, the entire contact 25 is formed of a suitable spring material, such as, for example, phosphor bronze, and the base portion 26 is curved to correspond with the curvature of the inner surface of tube 23. The portion 29 is angularly inclined to the base portion 26 and the resilient finger 28 is likewise inclined to the connecting arm 29. When the contacts 25 are attached to the flange 23, the resilient finger 28 of each of the contacts partially overlies the base portion 26 of an adjacent contact. The longitudinal length of the contacts 25 is made at least as great as the longitudinal length of the dielectric cylinders 9, 10 so that it is not possible to wedge these contacts between two adjacent disk electrodes to cause injury to the glass-to-metal seals. The innermost edges of the C-shaped portions 28 lie substantially on a circle having a diameter smaller than the diameter of the disk electrode 6 so that they firmly engage the edges of this electrode. Moreover, the arm portions of the C-shaped parts 28 are inclined at a slight angle with respect to the vertical stem portion connecting them to facilitate insertion of the disk electrode 6 into the contact 14, and to prevent the edges of the contacts from catching the disk electrode as it is inserted and withdrawn and injuring the glass-to-metal seals of the tube.

The metal blank used for forming the contact 15 for the tubular anode 7 is shown in Fig. 4 and the contact in assembled form is shown in Fig. 5. The unitary metallic blank 30 has a pair of bifurcated members 31, 32; a pair of base members 33, 34, to the former of which is attached the contact tab 17; and flexible loop portions 35, 36 connecting the members 33, 34, respectively, to the finger portions. The base portions 33, 34 are each provided with a pair of holes 37 which, when the contact is in assembled position, overlie and provide means by which the contact may be fastened to the supports 16 as shown in the apparatus of Fig. 1. As may be seen in Fig. 5, in assembly of the contact the bifurcated fingers 31, 32 are struck upwardly from the body of the blank 30 and their upper edges are bent outwardly more readily to receive a tubular contact. The flexible loops formed by the parts 35, 36 in the assembled contact permit considerable lateral and vertical movement of the fingers 31, 32 with respect to the base members 33, 34 so that the resultant contact structure assures ease in inserting a high frequency discharge device, even though certain eccentricities have entered into the dimensions of the device in its construction. From the foregoing, it is seen that my invention provides a new and improved resilient supporting and contact making arrangement for an electron

discharge device of the type having a disk-like electrode and a tubular electrode spaced apart along the axis of the device. The resilient fingers of the contact arrangement 14 guarantee that no injury will be caused to the glass-to-metal seal about the disk electrode 6, at the same time permitting considerable tolerance both in eccentricity and vertical position of this electrode. The flexible loop of the tubular electrode contact 15 likewise permits both vertical and lateral positioning in accordance with variations in the tubes used in such high frequency systems.

While I have shown a particular embodiment of my invention, it will of course be understood that I do not wish to be limited thereto since various modifications may be made, and I contemplate by the appended claims to cover any such modifications as fall within the true spirit and scope of my invention.

What I claim as new and desire to secure by Letters Patent of the United States, is:

1. A resilient supporting and contact-making arrangement for an electron discharge device of the type having a disk electrode and a tubular electrode spaced apart along the axis of said device comprising, a tubular conductive member, a plurality of resilient contacts conductively attached to the inner surface of said tubular member and extending inwardly therefrom, said contacts being adapted to engage said disk electrode and having innermost edges lying substantially on a circle of a diameter such that said contacts are compressed when said disk electrode is inserted therein, a contact for said tubular electrode including a plurality of resilient fingers adapted to engage said tubular electrode, said fingers being formed integrally with a supporting member and being connected therewith through a resilient loop, and means supporting said tubular member and said contact in spaced relation, adjacent edges of said resilient contacts and said contact being spaced apart longitudinally by a distance such that when said tubular electrode is passed through said member and inserted into said fingers, said resilient contacts engage said disk electrode.

2. A contact for a disk-like electrode comprising a tubular conductive member, and a plurality of resilient members conductively attached to the inner surface of said tubular member and extending inwardly therefrom, said members having innermost edges lying substantially on a circle of a diameter such that said resilient members are compressed when said electrode is inserted in said contact, each of said resilient members comprising a base portion affixed to said tubular member and a C-shaped portion inclined at an angle to a radius of said tubular member.

3. A socket for an electronic tube having a disk-like electrode comprising a flat member having a central aperture and a conductive flange therearound, a plurality of contacts, each of said contacts having a base portion attached to said flange and a resilient finger inclined at an angle to said base portion and projecting into said aperture from said flange, the resilient finger of each of said contacts partially overlying the base portion of an adjacent contact.

4. A contact for a disk-like electrode comprising a tubular conductive member, and a plurality of resilient members having a base portion conductively attached to the inner surface of said tubular member and a C-shaped contact portion inclined at an angle of from 20° to 60° with said conductive member and extending inwardly

therefrom, the contact portions of said resilient members having innermost edges lying substantially on a circle of a diameter such that said resilient members are compressed when said electrode is inserted in said contact.

5. A resilient supporting and contact-making arrangement for an electron discharge device of the type having a disk electrode and a tubular electrode spaced apart along the axis of said device comprising, a tubular conductive member, a plurality of resilient contacts conductively attached to the inner surface of said tubular member and extending inwardly therefrom, said contacts being adapted to engage said disk electrode and having innermost edges lying substantially on a circle of a diameter such that said contacts are compressed when said disk electrode is inserted therein, a contact for said tubular electrode including a plurality of resilient fingers adapted to engage said tubular electrode, means supporting said tubular member and said contact in spaced relation, means supporting adjacent edges of said resilient contacts and said contact in spaced relation, and resilient means supporting said contact whereby said contact may be moved longitudinally and laterally.

6. A contact for a tubular electrode comprising a metallic member having a pair of opposed bifurcated fingers forming a tube adapted to receive said electrode, said member having a web portion connecting said fingers and forming an end wall for said tube, said member including a pair of flexible arms extending outwardly from said web portion, said arms being bent to form a resilient loop, the ends of said arms remote from said web being overlapped to form a base portion, said arms having a length sufficient to permit substantial vertical and lateral movement of said fingers relative to said base portion.

7. A resiliently supported contact for a tubular electrode comprising a flexible metallic member having a pair of opposed upstanding fingers forming a tube adapted to receive said electrode, the free ends of said fingers being turned outwardly to facilitate entrance of said electrode into said tube, said member having a web portion connecting said fingers and forming an end wall for said tube, said member including a pair of flexible arms extending outwardly from said web portion, said arms being bent to form a resilient loop, the ends of said arms remote from said web being overlapped to form a base portion, said arms having a length sufficient to permit substantial vertical and lateral movement of said fingers relative to said base portion.
